TIMING DEVICE

Fritz Loeffler, New York, N. Y.

Application June 25, 1937, Serial No. 150,294

5 Claims. (Cl. 58—41)

This invention relates to timing devices, having particular reference to timing devices of the type wherein an electromagnetic oscillating motor operates intermittently to store up energy in a spring which drives a cooperating clockwork. The invention comprises improvements over the disclosures of United States Patents Nos. 1,993,411 and 2,000,600 and of copending application Serial No. 589,788 now Patent No. 2,089,280, granted August 10, 1937.

Generally, the object of this invention is to provide a novel device of the character indicated which shall be simple and efficient in construction, and positive and economical in operation over a wide range of voltages.

More specifically, an object of this invention is to provide a novel device of the character indicated in which one spring shall serve for storing and transmitting energy from the motor to the clockwork, and for operating a switch that makes and breaks the motor circuit.

Another object of this invention is to provide a novel device of the character indicated, wherein the switch for controlling the motor circuit shall be arranged to make a positive and sudden pressure contact, to maintain a sliding pressure contact during the contact interval, and to produce a sudden and positive break of the contact at the end of the contact interval so that sparking and fouling are minimized.

Another object of this invention is to provide a novel device of the character indicated wherein energy shall be stored in a driving spring and shall be constantly transmitted directly to a driving gear of the clockwork.

Another object of this invention is to provide a device of the character indicated, wherein the driving connection between the motor and the clockwork shall be so arranged that there is a minimum of lag and backlash when the motor tensions the driving spring.

A further object of this invention is to provide a device of the character indicated wherein the driving spring shall be so arranged that a constant torque is applied to the clockwork regardless of the degree of tensioning of the spring.

A further object of this invention is to provide a device of the character indicated wherein a means shall be provided for breaking the motor circuit if the device should cease to operate while the switch is in contact, so that damage to the device from overheating is obviated.

A further object of this invention is to provide a device of the character indicated wherein, if

desired, a sweeping or central second hand can be mounted in a novel manner.

A further object of this invention is to provide a device of the character indicated which shall have a novel and simple hand-setting arrangement.

A still further object of this invention is to provide a novel device of the character indicated wherein a light shall be provided and the holding means for the dial and glass shall also serve as a reflector.

A still further object of this invention is to provide a device of the character indicated which shall have a novel fastening arrangement for quickly and easily mounting it in a flat panel such as the dashboard of an automobile.

These and other objects of this invention, together with the manner of achieving them, will become evident in the following specification, taken together with the accompanying drawings, in which

Fig. 1 is a rear plan view of a device constructed in accordance with this invention with the casing broken away;

Fig. 2 is a sectional view taken along line II—II of Fig. 1;

Fig. 3 is a front plan view of the motor unit alone with the casing shown in section;

Fig. 4 is a section along the line IV—IV of Fig. 1, showing the positive or battery connection for the magnetizing coil and the heat-responsive fuse;

Fig. 5 is a section along the line V—V of Fig. 1, showing the negative or ground connection for the magnetizing coil;

Fig. 6 is a section along the line VI—VI of Fig. 1, showing the connection between the coil and the switch;

Fig. 7 is a rear plan view of the clock unit of a modified embodiment of this invention having a sweeping or central second hand;

Fig. 8 is a section along line VIII—VIII of Fig. 7, showing the central second hand construction;

Figs. 9, 10 and 11 are plan views of the switch in three different operating positions;

Fig. 12 is a section along the line XII—XII of Fig. 9, showing the means for mounting the several parts of the switch in relation to each other; and

Figs. 13 and 14 are sections along the line XIII—XIII of Fig. 1, showing the punched lugs before and after being twisted to indicate a preferred construction for attaching the casing of

the novel timing device to a flat plate, as, for instance, the dashboard of an automobile.

In accordance with this invention a timing device may comprise a motor unit, indicated generally by A, and a cooperating clockwork, indicated generally by B. The motor unit may comprise a stator having a frame 1 of Bakelite or other suitable non-magnetic insulating material and a rotor 2 of magnetic material, rotatably mounted in the frame 1 and adapted to oscillate relatively to the stator and periodically to tension a spring 3 to store energy therein. The energy stored in the spring is constantly transmitted to the clockwork through flexible members or clicks 4 fixed to the rotor and engaging directly in a driving gear of the clockwork, as will hereinafter more fully appear.

The frame 1 may be provided with an annular recess 5 in which are fixed a plurality of U-shaped magnetic pole pieces 6 at equal circumferential distances and an annular magnetizing coil 7 having a positive or battery connection 8 and a negative or ground connection 9. An annular, non-magnetic, insulating washer 10 may be provided for holding the coil 7 in place. Fixed in a centrally located opening through the frame 1 and substantially concentric with the coil 7 may be a bushing 11 having a rotor shaft 12 rotatably mounted therein. The rotor 2 is fixed to the front end of the shaft 12 by any suitable means and is preferably star-shaped, having a plurality of radial bars of magnetic material adapted to cooperate magnetically with the U-shaped pole pieces 6 of the stator, as shown in Fig. 3. The number of radial bars must be the same as the number of pole pieces. Fixed to the rear end of the rotor shaft 12 is a flat member 13 of non-magnetic conducting material, which serves as a lever to tension spring 3 when rotor 2 rotates in the direction shown by the arrows (Fig. 3) responsive to a current through coil 7. The member 13 also serves as part of a switch indicated generally by C for making and breaking the circuit through coil 7.

The switching mechanism may comprise a conducting member or brush 14 and a non-magnetic, non-conducting cam or lifting finger 15 pivotally mounted by means of a pivot 16 on member 13. The pivot 16 is preferably formed by bending down a portion of member 13, as shown in Fig. 12. The pivot 16 may be provided with a flat, extending portion 16a for slidably supporting lifting finger 15. The brush 14 may be pivotally mounted relatively to frame 1 by any suitable means. Such means may comprise a U-shaped portion 17 adapted to hook into a groove in the head of a bolt 18 fixed to frame 1 by any suitable means, as shown in Fig. 6. The bolt 18 may also serve to fasten and make contact with one end of coil 7 which extends through an opening 19 in the back of frame 1. The brush 14 is preferably provided with a hook 20 into which one end of spring 3 is hooked, and a contact 21 of special material adapted to make contact with a contact cam 22 fixed to member 13. The lifting finger 15 is preferably provided with an opening 23 into which the other end of spring 3 is hooked. Stops 24 and 25 may be provided on frame 1 to limit the rotational motion of member 13 which also limits the motion of rotor 2, since both member 13 and rotor 2 are fixed to rotor shaft 12 and thus rotate as a unit.

A stop 22a on member 13, preferably formed by bending down a portion of member 13, may be provided for cam 15. The stop 22a may have

a flat, extending portion 22b for slidably supporting cam 15.

Brush 14 may be provided with a slot 14a through which lifting finger 15 extends, and 5 an outwardly extending flat portion 28 adapted to cooperate with lifting finger 15, as will hereinafter more fully appear. Slot 14a serves to guide and slidably support both brush 14 and lifting finger 15 so that they maintain their 10 proper relative position at all times.

Spring 3 is tensioned between brush 14 and lifting finger 15 and thus constantly tends to press brush 14 into contact with contact cam 22 and lifting finger 15 against stop 22a. Spring 15 3 also pulls member 13 through pivot 16 against stop 24 in normal non-operating position. Thus an electric circuit is made from battery connection 8 through coil 7, bolt 18, brush 14, contact 21, contact cam 22, member 13, shaft 12, bushing 11, and through a suitable conductor 26 from bushing 11 to the ground connection 9.

When current passes through this circuit the coil 7 magnetizes pole pieces 6, which attract the magnetic bars of the rotor 2 and cause it to rotate in the direction indicated to a position such as is indicated by the dotted lines in Fig. 3. The switch at the same time passes through 25 the cycle of operations indicated in Figs. 9, 10 and 11. Lifting finger 15 rotates with member 13 until hook portion 27 of lifting finger 15 engages flat portion 28 of brush 14, after which lifting finger 15 pivots around pivot 16 away from stop 22a until the position shown in Fig. 10 is reached. It will be seen that up to this point a sliding pressure contact has existed between contact 21 and contact cam 22 which keeps the contacts clean and effective. The portion 30 28 of brush 14 now suddenly clears the hook portion 27 of lifting finger 15 and is snapped out of contact by a curved portion 29 thereof under tension of spring 3, which pulls lifting finger 15 back against stop 22a as shown in Fig. 11. This breaking of contact preferably occurs when the bars of rotor 2 have covered one-quarter to 40 one-third of pole pieces 6, momentum carrying the rotor an additional distance, further tensioning spring 3. The energy stored in spring 3 is now transmitted through lifting finger 15, pivot 16, member 13, rotor shaft 12, rotor 2, and clicks 4, to a driving wheel 39 of the clockwork over which clicks 4 have slid when rotor 2 was tensioning spring 3. Since the speed of this action is so great, there is no back drag and no appreciable interruption in the force applied to the 45 driving gear. As the clockwork is driven by spring 3, rotor 2 gradually returns to its initial 50 position until brush 14 suddenly drops off of curved surface 29 into contact with contact cam 22, when the cycle is repeated.

It will be seen from the foregoing description that as rotor 2 tensions spring 3, the lever arm through which spring 3 acts to drive the clockwork, becomes less. This results in substantially constant torque being applied to the clockwork 55 regardless of the degree of tensioning of spring 3. It will also be seen that spring 3 serves as a single means for storing energy to drive the clockwork and for operating the switch to make a sudden contact, to hold a pressure contact during the contact period, and to break the contact 60 suddenly responsive to rotation of the rotor.

The clockwork denoted generally by B may comprise two parallel fixed plates 30 and 31, spaced and held together by spacing lugs 32, a dial backing plate 33, a dial 34, a central or

minute shaft 35 rotatably mounted in plates 30 and 31 and carrying a minute hand 36 fixed to the end thereof, an hour shaft 37 rotatably mounted on the shaft 35 in geared relation thereto in a well-known manner and carrying an hour hand 38 fixed to the end thereof, a center or driving gear 39 frictionally engaging the central shaft 35 through a washer 40 fixed to shaft 35 and a spring washer 41, and a gear train driven by the center gear 39 and controlled by an escapement, a balance wheel 42, and a hairspring 43, all of well-known, conventional arrangement and therefore not fully shown in the drawings. A shaft 44, together with cooperating mechanism, may be provided for adjusting the hair spring 43 and regulating the clock movement. For attaching the clockwork to the frame 1 of the motor unit there may be provided a ring plate 45 fixed to plate 30 by screws 46, spacing lugs 47 fixed to ring plate 45, and bolts 48 passing through openings in frame 1 and screwing into lugs 47, as shown in Fig. 5. The motor unit and clockwork are preferably mounted relatively to each other in such a manner that rotor shaft 12 and central shaft 35 are in substantially axial alignment.

It is an important part of this invention that the flexible clicks 4 fixed to one of the bars of rotor 2 engage directly in the teeth of center gear 39 so that energy stored in spring 3 by rotor 2 is transmitted directly to center gear 39 without any intermediate gears or linkages. Openings (not shown in the drawings) are provided in plates 30 and 31 to accommodate clicks 4 over the full range of movement of rotor 2. A plurality of clicks is preferably provided having spaces between their ends slightly greater than the pitch of the teeth of center gear 39, so that each click drops in at a different instant when rotor 2 tensions spring 3 and drag and backlash are minimized. For smoothest operation, the space between the click ends should be

$$\left(1 + \frac{1}{n}\right)p$$

where n is the number of clicks and p is the pitch of the teeth in which they engage. With such a ratchet mechanism, the action is the same as a single click engaging n times the number of teeth in the same linear distance.

In a preferred embodiment of this invention, a novel means is provided for setting the hands relatively to the clockwork from the back of the motor unit. In this embodiment, the rotor shaft 12 is hollow and has loosely mounted therein a shaft 49 having a knurled knob 50 fixed to the outer end thereof and a crank 51 at the other end thereof. Fixed to the inner end of the central or minute shaft 35 may be a flat disk 52 having a slot 53 therein adapted to cooperate with crank 51, which fits rotatably and slidably into the slot 53. Then by turning knob 50 shaft 35 can be turned relatively to center gear 39 against the friction of washer 41, even though wide misalignment between shaft 35 and rotor shaft 12 exists. With shaft 35, hands 36 and 38 are turned in geared relation to each other.

For preventing damage to the coil or any other part of this device, if the rotor should fail to operate when the switch is closed or in contact, there is provided in accordance with this invention means responsive to heat generated in the coil for breaking the circuit therethrough before any damage can be done. Such means may comprise a low-melting alloy conductor 54 interposed

in the circuit between the positive terminal 8 and the coil 7. The conductor 54 may be held at one end by a bolt 55, to the upper end of which the terminal 8 is connected, and a nut 56 (Fig. 4), and at the other end by a bolt 57 which also holds one end of the coil 7 extending through an opening 58 in frame 1. The conductor 54 melts responsive to heat generated in coil 7, but not within itself, thus breaking the circuit 10 through coil 7.

A modified form of clockwork in accordance with this invention, having a novel central or sweeping second hand arrangement, is shown in Figs. 7 and 8. In this embodiment three parallel, spaced plates 59, 60 and 61 are provided. A shaft 62 is rotatably mounted in plate 59 and carries a second hand 63 fixed to an end thereof. A hollow minute shaft 64, surrounding and substantially concentric with shaft 62 but spaced therefrom, is rotatably mounted in plates 60 and 61 and carries a bushing 65 frictionally engaging it on which is mounted a minute hand 66. A bearing 67 between shaft 62 and shaft 64 provides the only other positive mounting for shaft 62 besides plate 59. Rotatably mounted on bushing 65 and geared in relation thereto in a well-known manner, is a shaft 68 carrying an hour hand 69. A center or driving gear 70 is fixed to shaft 64 and is driven by clicks 4 fixed to rotor 2 in the same manner as previously described. Power is transmitted from gear 70 to pinion 71, from gear 72 mounted on pinion 71 to pinion 73 mounted on shaft 62, and from gear 74 fixed to pinion 73 to pinion 75 which is fixed to escape wheel 76. This novel construction is of advantage because it allows relatively wide misalignment between shafts 62 and 64 without causing binding therebetween or interfering with proper operation in any way. A shaft 76^a cooperating with a conventional gear train may be provided for setting hands 66 and 69 independently of shaft 64 against the friction between bushing 65 and shaft 64.

A timing device in accordance with this invention may be enclosed in a suitable casing 77 which may be secured to the frame 1 by any suitable means such as the screws 78 and the rubber grommets 79 fixed to bolts which also serve to hold the motor and clockwork together and the positive and negative terminals 8 and 9, respectively, of the electric circuit. These latter terminals may be additionally protected by a small casing 80 fixed to casing 77 in any suitable manner. For protecting the set knob 50 which protrudes through an opening in casing 77 against contact and dust, a removable cap 81 is provided therefor, which may be removably secured to casing 78 in any suitable manner.

Mounted within casing 77 in such a manner that it can be easily removed, may be an electric light 82 for lighting up the hands and dial of the clockwork. A glass 83 which may also carry numbers to indicate divisions of time, may be provided in front of dial 34 and held in place by suitable means such as member 84 and bezel 85 crimped over the edge of casing 77. The member 84 is preferably polished to act as a reflector for directing light from lamp 82 over dial 34 and into the edge of glass 83 for illuminating the same.

Referring now to Figs. 12 and 13, there is shown a novel means for attaching the novel timing device to a flat plate, as, for example, the dashboard of an automobile. A plurality of lugs 86 punched out with the casing 77 are provided to be slipped through slots 87 in the cooperating

plate, after which the lugs can be twisted to secure the casing to the plate. This provides a quick, firm and inexpensive means of mounting the casing 11 wherever desired.

It is, of course, contemplated that certain changes, substitutions and modifications may be made in the novel timing device hereinbefore described without departing from the spirit or scope of this invention, as defined in the appended claims. It is, for instance, possible to insert a spiral, energy-storing spring between clicks 4 and center gear 39, in which case rotor 2 will go through several cycles in quick succession until the tension of this second spring balances the tension of spring 3, after which cycles will repeat in their normal period. This would permit the current source to be cut off for a considerable length of time without interfering with the operation of the clockwork which would be driven by the energy stored in the second spring.

What is claimed is:

1. In a timing device, a motor having a stator and a rotor, a hollow shaft for rotatably mounting said rotor, a clockwork cooperating with said motor, a central shaft forming part of said clockwork in substantially axial alignment with said rotor shaft and carrying a time-indicating means at one end thereof, and means including a member fixed to the other end of said central shaft and a crank rotatably mounted in said rotor shaft and rotatably and slidably cooperating with said member for setting said time indicating means.

2. In a timing device, a motor having a stator and a rotor, a hollow shaft for rotatably mounting said rotor, a clockwork cooperating with said motor, a rotatably mounted central shaft for said clockwork in substantially axial alignment with said rotor shaft and carrying a minute hand at one end thereof, an hour shaft rotatably mounted on said central shaft in geared relation thereto and carrying an hour hand at the end thereof, and means including a disk having a slot therein fixed to the other end of said central shaft and a shaft rotatably mounted in said rotor shaft and having a crank at one end thereof adapted to cooperate with said slot for setting said hands independently of said clockwork.

3. In a timing device, a motor having a stator and a rotor, a clockwork cooperating with said

motor, a casing for said motor and clockwork having an opening in the rear thereof, a hollow shaft for rotatably mounting said rotor, a rotatably mounted central shaft for said clockwork in substantially axial alignment with said rotor shaft and carrying a minute hand at one end thereof, an hour shaft rotatably mounted on said central shaft in geared relation thereto and carrying an hour hand at one end thereof, means including a disk having a slot therein fixed to the other end of said central shaft and a set shaft rotatably mounted in said rotor shaft and having a crank at one end thereof adapted to cooperate with said slot for setting said hands independently of said clockwork, means for turning said set shaft protruding through the opening in said casing, and cover means removably secured to said casing and covering said opening for protecting said turning means.

20 4. In a timing device, a motor comprising a stator having a coil and a rotor arranged to rotate when an electric current is passed through said coil; a clock work cooperating with said motor; an electric switch adapted to close an electric circuit through said coil and cause rotation of said rotor; and a single spring for storing all the energy produced by intermittent rotation of said rotor, which spring constitutes the sole power means for closing said switch, for holding said switch closed while said rotor rotates through a predetermined angular distance, for opening said switch after said rotor has rotated through said predetermined angular distance, for driving that clockwork and for returning said rotor to starting position.

25 5. In a timing device in cooperation with a clockwork, a switch comprising contacts and a contact making and a contact breaking member, a single spring, a motor comprising a coil, a stator and a rotor for intermittently furnishing the energy to be stored in said single spring, said spring being floatingly suspended between said contact making and breaking members so that it causes the sudden closing of the contacts, the holding 30 of the contacts in closed position during the rotation of the rotor through a predetermined angular distance, and the sudden opening of the contacts after said rotor has moved through said angular distance and the return of the rotor into starting position while driving the clockwork.

FRITZ LOEFFLER.
